Albert Wiss
INVENTOR

UNITED STATES PATENT OFFICE.

ALBERT WISS, OF CORTLANDT TOWNSHIP, NEW YORK.

DESIGN FOR A WATCHCASE, MEDAL, OR SIMILAR ARTICLE.

• 54,492.

Specification for Design.

Patented Feb. 10, 1920.

Application filed June 28, 1919. Serial No. 307,490. Term of patent 7 years.

To all whom it may concern:

Be it known that I, ALBERT WISS, a citizen of the United States, residing in Cortlandt township, in the county of Westchester and State of New York, have invented a new, original, and ornamental Design for a Watchcase, Medal, or Similar Article, as shown, of which the following is a specification, reference being had to the accompanying drawing, forming part thereof.

The figure is a plan view showing the back of a watch case or a medal.

I claim:

The ornamental design for a watch case, medal, or similar article as shown.

ALBERT WISS.
